UNITED STATES PATENT OFFICE.

WILLARD HONBAUM, OF DETROIT, MICHIGAN.

GAS-RANGE TOP.

1,366,659.

Specification of Letters Patent. Patented Jan. 25, 1921.

Application filed April 15, 1920. Serial No. 374,000.

To all whom it may concern:

Be it known that I, WILLARD HONBAUM, a citizen of the United States of America, residing at Detroit, in the county of Wayne 5 and State of Michigan, have invented certain new and useful Improvements in Gas-Range Tops, of which the following is a specification, reference being had therein to the accompanying drawings.

10 The invention relates to gas stoves of the open top type and refers particularly to closed tops for detachably fitting the open tops. The invention has for its object the novel arrangements and combination of 15 parts as more fully hereinafter set forth.

In the drawings:

Figure 1 is a perspective view of the construction embodying my invention, in inverted position;

20 Fig. 2 is a cross section on the line 2—2 of Fig. 1;

Fig. 3 is a cross section on the line 3—3 of Fig. 1.

It has been the usual practice heretofore 25 to apply closed tops to open top stoves with the upper surfaces of the closed tops parallel to the upper surfaces of the stoves and in a horizontal plane. There being no flue for inducing a draft to carry away the combustion 30 gases from the burners, proper combustion did not take place at the burners so that objectionable odors occurred. With my invention draft is induced to carry the combustion gases away from the burners so that 35 the gases being burned will have proper combustion.

In detail, 1 is an open top and 2 are the 40 burners of a gas stove. 3 are coöperating closed tops for detachably fitting the open top 1, the number of closed tops depending upon the size of opening in the open top.

These closed tops are exactly alike and therefore but one will be described.

Each closed top 3 is positioned upon the 45 open top 1 by means of the adjustable stops 4 which have depending flanges adapted for engagement with the edges of the opening in the open top. Each closed top is provided with the apertures 5 adapted to register above the burners 2 and also adapted for engagement with suitable covers or lids 6. 7 is a depending director flange upon the top

plate comprising the parallel side portions 8 and the semi-circular portion 9 at the front of the front opening 5 and connecting the 55 forward ends of the parallel portions 8, these parallel portions 8 being at the opposite sides of the apertures 5.

For the purpose of inducing a draft to carry the combustion gases away from the 60 burners the top plate 3 is provided with side flanges 10 which rest upon the open top 1 of the stove and are of greater depth at the rear of the top plate than at its front. This arrangement of side flanges inclines the 65 surface of the top plate upwardly from front to rear which consequently assists the combustion gases in moving away from the burners 2. 11 is a front depending flange extending between the forward ends of the depending side flanges 10. 12 are elongated 70 apertures in the rear surface of the top plate 3 for permitting of the more ready removal of the combustion gases and 13 are suitable reinforcements bridging these elongated 75 apertures and strengthening the rear end of the top plate.

From the above description it will be readily seen that the upward inclination of the top surface of the closed top induces a 80 draft of the combustion gases away from the burners and at the same time the closed top is adapted to effect its normal functions of supporting utensils above the burners without danger of tipping of the utensils. 85

What I claim as my invention is:

1. The combination with a gas stove having an open top, of a plane-surfaced closed top removably mounted on said open top and provided with depending side flanges resting 90 on said open top, the depth of said side flanges being greater at the rear than at the front.

2. The combination with a gas stove having an open top, of a plane-surfaced closed 95 top removably mounted on said open top and provided with depending front and side flanges resting on said open top, the depth of said side flanges being greater at the rear than at the front, whereby said closed top 100 inclines upwardly from the front to the rear and relative to said open top.

In testimony whereof I affix my signature.

WILLARD HONBAUM.
